UNITED STATES PATENT OFFICE.

ROBERT S. MOSS, OF CHICAGO, AND ARTHUR ROBERTS, OF EVANSTON, ILLINOIS.

COKE-OVEN.

1,239,870.

Specification of Letters Patent. Patented Dec. 31, 1918.

Application filed January 7, 1914, Serial No. 810,809. Renewed March 23, 1918. Serial No. 224,388.

To all whom it may concern:

Be it known that we, ROBERT S. MOSS and ARTHUR ROBERTS, both citizens of the United States, and residing at Chicago, Illinois, and at Evanston, Illinois, respectively, have invented certain new and useful improvements in Coke-Ovens, of which the following is a specification.

The present invention has reference to certain improvements in coking processes and to the construction and arrangement of a furnace or oven for carrying such process into effect. While the construction herein disclosed is especially intended for use in practising the process herein disclosed, still it will presently appear that many of the novel features of the oven construction can be successfully and advantageously used in the practice of other processes than that particularly set forth herein.

Another object of the invention is to so construct the oven and adjacent or associated parts that the temperature of the distillation products will be maintained at substantially the same value as that at which the products were distilled until the hydraulic main is reached, thereby insuring against premature precipitation of carbon in the form of "soot" or lamp black, etc.

Another object of our invention is to provide a distillation process in which the temperature of the distillation products is maintained substantially constant from the time they leave the carbonizing mass until they reach the hydraulic main, and to provide a construction of oven and associated mechanisms for carrying such process into effect.

Another object of the invention has reference to the preheating of the incoming air so that by the time it enters the combustion flues it will be of very high temperature. In this connection a further object is to provide a construction such that the preheating of the air may be accomplished by absorption of the waste heat from the outgoing products of combustion.

In order to carry forward this extraction of heat from the waste products of combustion in the most efficient and complete manner, we have so constructed the flues for the incoming air and for the outgoing waste products of combustion that a "counter-current" flow is produced, that is one in which the cold air first comes under the influence of the coldest portions of the waste products of combustion, and in which the air of increasing tem-

perature comes successively under the influence of hotter and hotter portions of the waste combustion products. It is well understood with such an arrangement a most efficient and complete heat transfer may be effected, and also that the ultimate economic temperature to which the air may be raised is much higher than that which can be obtained with any other arrangement.

Still further in connection with the foregoing object it is desired to so relate the preheating flues or passages to the retort and other portions of the oven that the gases may be passed from point to point in the most direct and economical manner possible. To this end we have assembled the complete structure in the form of a "superstructure" and a "substructure," placing the retort and combustion flues in the superstructure, and placing the preheating flues and passages in the substructure.

Other objects and features will appear from a detailed description of the invention, which consists in the features of construction and combinations of parts hereinafter described and claimed.

In the drawings:

Figure 1 is a vertical section taken through a single unit coke oven on line 1—1 of Fig. 5, looking in the direction of the arrows:

Fig. 2 is a similar section taken on line 2—2 of Fig. 5, looking in the direction of the arrows;

Fig. 3 is a horizontal section through the base or substructure of a single unit coke oven taken on line 3—3 of Fig. 1, looking in the direction of the arrows;

Fig. 4 is an enlarged vertical section of a portion of a single unit base or substructure showing the use of checkerwork in the various air flues and product of combustion flues;

Fig. 5 is a horizontal section through a single unit coke oven taken on line 5—5 of Fig. 1, looking in the direction of the arrows; and

Fig. 6 is an enlarged horizontal section of one end of a single unit coke oven taken on line 6—6 of Fig. 1, looking in the direction of the arrows.

As a matter of convenience in illustration, and simply for the purpose of showing one manner of applying the features of invention to which the present disclosure relates, we have shown said features as applied to an oven construction embodying certain of

the features shown and described in Letters Patent of the United States No. 1,025,419, issued May 7, 1912, to Robert S. Moss. However, it will be understood that in so illustrating the present features of invention we do not in any wise limit ourselves to their application in this particular manner.

In the several drawings, the coke oven proper and the combustion flues for heating the same are shown as built into a "super-structure", 7, while the passages or flues for the eduction of the burnt gases and for the preheating of the incoming air are shown as contained mainly in a "sub-structure" 8. The retort for the coal or other carbonizing material is designated 9. A plurality of combustion flues 10 are arranged in U-shaped fashion around the sides and bottom of the coking retort. Into the upper portion of each of these combustion flues there depends a fuel nozzle or the like 11 adapted to receive its supply of fuel from a manifold or main 12 which extends throughout the length of the oven. An air flue 13 extends upward in the superstructure adjacent to one side of each of the U-shaped combustion flues, communicating with the induction end of such combustion flue under the control of a sliding or gate valve 14. This valve may be conveniently constructed as a plate extending throughout substantially the entire length of the oven, being provided with a perforation corresponding to each of the combustion flues which it is intended to control. In accordance with the principles disclosed in the above mentioned Letters Patent, the particular arrangement herein represented is one in which the induction ends of the combustion flues alternate on the two sides of the retort, so that the flow of burning gases in each combustion flue is in the direction opposite to that in the adjacent flues. This arrangement will be readily understood from an inspection of Figs. 1 and 2 which are sections taken through adjacent portions of the structure. One of the upper ends 15 of each combustion flue communicates with a downwardly extending flue 16, the lower end 17 of which bends over and communicates with a longitudinally extending discharge flue 18 which leads to the stack or other draft producing means as best shown in Fig. 3. The arrangement thus far described is of familiar construction, and we will not further detail the same at this point.

In order to carry the distillate gases immediately away from the carbonizing mass a pair of passages 19 extend throughout the length of the oven, being conveniently located in the upper or roof portion of the super-structure. A plurality of communicating ports or the like 20 extend from the upper portion of the retort into the pas-

sages 19, said ports being conveniently spaced, preferably in alternate relation throughout the length of the oven so as to permit the distillation products to rise from the retort into the passages 19 without having to travel any appreciable distance. With this arrangement it will be apparent that "cracking" or "splitting" of the products will be overcome inasmuch as they will not remain for any appreciable length of time in contact with the hot walls of the retort.

In order to still further insure that the temperature of the distillation products will not rise above their distillation temperature and in order to better control the coking operation, it is preferred that the temperature of the upper or roof portion 21 of the retort proper shall be maintained approximately at the temperature at which the products of distillation are passing off. As a simple means accomplishing this result we provide a "dome" above the carbonizing material, which dome is not directly heated by the combustion flues, and into which dome the distillation products immediately rise. In the particular arrangement illustrated this dome constitutes the upper portion of the retort, and the upper ends of the combustion flues do not extend into the walls of the dome but terminate below it so that it is not directly heated. While we have herein shown the "dome" as being the upper portion of the retort, and as being the portion which is not directly heated by the combustion flues, such construction being shown by way of illustration, still it will be seen that there are peculiar relationships between a dome placed in the upper portion of the retort and the particular arrangement of heating flues illustrated. For example, the gases of combustion in the heating or combustion flues are being drawn down away from the dome, so that the fact that they do not directly heat the dome is all the more pronounced.

It will be seen from a study of the arrangement thus far particularly considered, that the dome and the passages are so related and inclosed that the products of distillation passing off through them are not cooled but are allowed to pass off at the same temperature as that at which they are distilling. It, therefore, follows that the arrangement is such that the products of distillation are neither cooled to cause them to precipitate their tarry constituents, nor heated above their temperature of distillation to cause them to break down or crack into lighter or poorer constituent gases.

Each of the air flues 13 has its lower end 22 in communication with a longitudinally extending passageway 23. By reason of the alternating relationship of the U-shaped combustion flues, each of the air flues 13

occupies a position within the structure corresponding to the discharge flue 16, and this fact will be readily apparent from an examination of Figs. 1 and 2. Therefore, in order to accommodate the air flues 13 on both sides of the structure there is a flue 23 extending along each side of the substructure, each flue 23 supplying air to the corresponding flues 13.

10 From an examination of Fig. 3, it will be seen that the flues 23 communicate at their rear ends with other longitudinally extending air flues 24, which, in turn, are provided with the inlet openings 25 communicating 15 with the atmosphere. The openings 25 are adjacent to the discharge end of the flue 18 which leads to the stack or other draft producing or discharging means so that the cold air first entering the flues 24 travels 20 backward in the direction of the arrows of Fig. 3, while the waste products of combustion are traveling forward as shown also by the arrows in said figure. It, therefore, follows that a counter-current flow of incoming 25 air and waste products of combustion is produced, the air coming constantly under the influence of products of combustion of higher and higher temperature as it passes rearwardly. By the use of this counter-current 30 flow arrangement there is maintained a substantially constant difference of temperature between the two surfaces of the partitions 26 which separate the flues 24 from the flue 18, and therefore the rate of transfer 35 of heat through these partitions is practically constant at all points throughout its area. It is well understood that such an arrangement is capable of transferring a maximum number of heat units through a wall 40 of given heat conductivity and area within a specified interval of time, and by this arrangement therefore a maximum of heating capability is obtained. Furthermore, by the use of a counter-current construction, 45 the difference in temperature between the air and the waste products of combustion at the rear end of the structure is substantially the same as that at the front or air admission end, from which it follows that 50 the incoming air ultimately attains a temperature very nearly as high as the temperature of the waste products of combustion when they first enter the flue 18.

As the air travels forward through the 55 flues 23, it is tapped off from time to time into the lower ends 22 of the flues 13, so that its volume continually diminishes as it passes forward in the flues 23. There will be a tendency for the heat contained in the 60 air within the flues 23 to transfer through the partitions 27 into the adjoining flues 24, and therefore it might be expected that the temperature of the air in the flues 23 would again be reduced as said air traveled 65 forward. It will be noted, however, that

the flues 16 for the products of combustion extend down between the consecutive flues 13, and adjacent to the flues 23. It, therefore, follows that, as the air travels forwardly in the flues 23, heat will be transferred through the partitions 28 which separate the flues 16 from the flues 23, this transfer of heat very largely, if not entirely, offsetting the aforementioned transfer through the partitions 27. By reason of the relative 70 arrangements of the flues as above described, it will be found that when the air is first admitted to the induction ends of the combustion flues, it will have a temperature substantially equal to the temperature of the 80 waste products of combustion as they pass down through the flues 16, with a consequent large saving in fuel consumption, and with a correspondingly higher temperature of combustion. This is an extremely important 85 factor in an arrangement of this kind, inasmuch as the coking possibilities are largely determined by the ultimate temperature which can be attained within the retort.

90 In order to further facilitate the transfer of heat from the waste products of combustion to the incoming air, we may prefer to provide checkerwork in the various flues 23, 95 24, and 18, substantially as shown in Fig. 4. This checkerwork serves to conduct heat from the interior or central portions of the products of combustion flues into the partitions, and also to conduct the heat from the partitions into the interior or central portions of the air flues. In other words these checkerworks performs a heat conducting function as distinguished from a heat storing function, and, therefore, serve chiefly the function of providing a larger surface of 100 contact for the transfer of heat from the waste products of combustion and to the incoming air.

105 In order to control or regulate the temperature within the retort from time to time, 110 the rate of delivery of the fuel through the mains 12 can be controlled or adjusted, so that the temperature can be changed from time to time during the coking process and according to the instantaneous needs or 115 desires of the operator.

We claim:

1: The combination with a coke oven having heating walls, each heating wall being provided with a plurality of vertical passages, alternate passages of each heating wall being spent gas passages, and the intermediate passages of said wall being air passages, of a sub-structure on which said oven is mounted, said sub-structure being provided 120 with a longitudinal spent gas tunnel, connections from the lower ends of the spent gas passages to said tunnel, an incoming air tunnel adjacent to each side of the spent gas tunnel, the inlet ends of the air tunnels being 125 130

adjacent to the discharge end of the spent gas tunnel, other longitudinal air tunnels in the sub-structure lying adjacent to the first mentioned air tunnels and having their back 5 ends connected to the back ends of the first mentioned air tunnels, and connections from each of the second mentioned air tunnels to the lower ends of the adjacent air passages.

2. The combination with a coke oven having heating walls, each heating wall being provided with a plurality of vertical passages, alternate ones of the passages in each heating wall being spent gas passages, and the intermediate passages of said heating wall being air passages, of a sub-structure on which said coke oven is mounted, said sub-structure having a longitudinally extending spent gas tunnel, a pair of air tunnels lying adjacent to said spent gas tunnel, other air tunnels lying adjacent to said first mentioned air tunnels and in communication therewith, connections from the lower ends of the spent gas passages to the spent gas tunnel, and connections from the lower ends 20 of the air passages to the adjacent ones of the second mentioned air tunnels.

3. The combination with a coke oven having heating walls, one of said heating walls being provided with a plurality of vertical passages, selected ones of said passages being spent gas passages, and other of said passages being air passages, of a sub-structure on which said oven is mounted, said sub-structure being provided with a spent gas tunnel, and with a U-shaped air tunnel, one arm of said U-shaped air tunnel lying adjacent to the spent gas tunnel, connections

from the lower ends of the air passages to the other arm of said U-shaped air tunnel, and connections from the lower ends of the 40 spent gas passages to the spent gas tunnel.

4. The combination with a coke oven, having a heating wall provided with a plurality of vertical passages, selected ones of said passages being spent gas passages, and other 45 of said passages being air passages, of a sub-structure on which said oven is mounted, said sub-structure being provided with a spent gas tunnel, and with a U-shaped air tunnel, one portion of said air tunnel lying adjacent to the spent gas tunnel, connections from the lower ends of the air passages to another portion of said air tunnel, and connections from the lower ends of the spent gas 50 passages to the spent gas tunnel. 55

5. The combination with a coke oven, having a heating wall provided with a plurality of passages, selected ones of said passages being gas passages and other of said passages being air passages, of a sub-structure on 60 which said oven is mounted, said sub-structure being provided with a spent gas tunnel and with a U-shaped air tunnel, one portion of said air tunnel lying adjacent to the spent gas tunnel, connections from the lower ends 65 of the air passages to said air tunnel, and connections from the lower ends of the spent gas passages to the spent gas tunnel.
